METHOD OF MAKING SHOES

Sidney J. Finn, Beverly, Mass., assignor to United Shoe Machinery Corporation, Borough of Flemington, N. J., a corporation of New Jersey

Application October 3, 1938, Serial No. 232,929

9 Claims. (Cl. 12—142)

This invention relates to methods of making shoes and is herein described as practiced in the making of ladies' pumps.

In the manufacture of shoes it is customary to stitch together a lining and an upper, to place a stiff molded counter between them at their heel portions, and to mount this assembled member together with an insole upon a last. A temporary limp box toe is placed between the upper and the lining at their toe portions and then the pulling-over and side-lasting operations follow. The tack which holds the extreme toe portions of the upper lining and box toe is removed, and the greater part of the lasting allowance 5 of the box toe is cut out; after which the toe and heel are lasted and the subsequent operations performed including the attaching of the outsole and the heel. It is difficult with this method to cause the heel end of the assembly, which includes the upper, the lining, and the counter, to take the exact shape of the heel portion of the last. The difficulty is due largely to the presence of three layers of material to be shaped and to the fact that the molded counter does 10 not have initially the exact shape of the heel portion of the last and must be conformed to it more or less. Also after the shoe has been pulled over, it is difficult satisfactorily to trim off the surplus material of the lasting allowance 15 of the box toe.

According to the present invention the parts are all, or for the most part, mounted separately upon the last or upon each other, the lining being pulled over before the upper is mounted upon it and the upper and lining being separately conformed to the last and subsequently being fastened together along their upper edges. By this method of procedure in which the parts are all, or for the most part, conformed separately to the last and the surplus material of the box toe can be more readily and accurately removed, a shoe results which is as nearly as possible the exact counterpart of the last upon which it was made.

Referring now to the accompanying drawings, Fig. 1 is a perspective of the shoe the lining of which has been pulled over and partially lasted;

Fig. 2 is a perspective of the machine for conforming the heel end of the lining and the counter to the heel end of the last;

Fig. 3 is a perspective of the shoe after the completion of the lasting of the lining and after having been operated upon by the machine of Fig. 2;

Fig. 4 is a perspective showing the trimming off of surplus material from the lasting allowance of the box toe;

Fig. 5 is a perspective of the shoe after the upper has been lasted, certain portions of the overlasted margin of the upper having been pulled up to show the cement;

Fig. 6 is an elevation of the shoe ready to have the last pulled and the lining and upper stitched together along their upper edges;

Fig. 7 is a section on an enlarged scale on the line VII—VII of Fig. 6;

Fig. 8 is an elevation of the forepart of the finished shoe; and

Fig. 9 is a section on an enlarged scale on the line IX—IX of Fig. 8.

In carrying out the method (Fig. 1) a lining 15, which as shown is in two parts, is mounted together with an insole 17 upon a last 19 and pulled over and lasted, a cement such as latex 20 being employed, the upper edge of the lining around what will be the foot opening in the finished shoe being fastened to the last by tacks 25 21. A molded counter 23 (Fig. 3) coated on its inner face with cement such as latex is placed 25 over the heel end of the lining and subjected to a conforming operation, for example to the action of a conforming machine such as that shown in Fig. 2.

This machine comprises a support 25 for the 30 last, a deformable rubber pad 27 having in its forward portion a generally U-shaped recess to receive the heel portion of the partly fabricated shoe, and a second deformable rubber pad 29. The rubber pad 27 is mounted in a two-part frame 31 the parts of which are hinged together about a pivot 33 carried by the frame of the machine and may be swung from open to closed position and back again by suitably operated links one of which is shown at 35, said links being each pivoted at one of their ends to one of the parts of the pad frame 31, the pivot for the link 35 being shown at 37. The upper pad 29 is carried by a plate 39 the upright stem of which is vertically slidable in a bore in an overhanging arm 41 of the frame of the machine and is provided with a rack 43 with which meshes a pinion, not shown, on a horizontal shaft 45 rotatably mounted in the overhanging arm and having at one end spokes 47 by which it may be turned to raise and lower the pad 29. The parts of the pad frame 31 are first swung open to permit the heel end of a lasted shoe to be placed upon the support and are then closed to cause the wings and rear wall of the counter to be conformed 45 50 55 55

to the shape of the heel portion of the last. This is the position of parts shown. Thereafter, the shaft 45 is rotated to conform the inturned flange of the counter to the shape of the adjacent bottom surface of the last. The counter thus conformed is held in place by the cement.

As an alternative to that part of the method which has been thus far described a partly molded counter in the form commonly referred to as "clam shell" and the heel end of a lining with cement between them may be placed in a counter molding machine and molded together. The molded counter and lining may then be mounted together with an insole upon a last and pulled over and lasted, after which the heel portion of the partly fabricated shoe may be subjected to conforming pressure, for example, by means of the machine shown in Fig. 2. In either case the shoe at this stage of its manufacture will have the appearance shown in Fig. 3, the lining and the counter being conformed exactly to the adjacent portion of the last.

A limp box toe 49 (Fig. 4) such for example as one made of fabric impregnated with pyroxylin and soft or limp by reason of the presence in it of a volatile solvent, such as acetone, is now placed on the toe end of the lining and conformed to the toe portion of the last, after which the surplus material, which consists of the greater part of the lasting allowance of the box toe, is trimmed off, for example by means of a hand knife 51.

An upper 53 (Fig. 5) is mounted upon the lining, box toe, and counter and lasted, the overlasted margin being fastened to the overlasted margin of the lining and the inturned flange of the counter in any suitable manner, for example by cement such as latex, and also in the heel seat portion by tacks 52. The upper edge of this upper has previously been finished, for example in the manner shown in Figs. 7 and 9, by means of a strip of binding 55 which is first stitched at 57 to the display side of the upper and then folded about the attached portion and about the edge of the upper and cemented to the flesh side of the upper. The further manufacture of the shoe proceeds as usual including the attaching of an outsole 59 and a heel 61. The tacks 21 which fasten the upper edge of the lining 15 to the last are removed, and the last is pulled. The upper and lining around the foot-opening of the shoe now have the appearance best shown in Fig. 7, the lining 15 projecting above the edge of the upper 53. The lining and upper are fastened together by stitches 63 after which the surplus projecting portion of the lining is trimmed off, the finished shoe having the appearance shown in Fig. 8.

Although the invention has been described as a series of steps performed in a certain order, it should be understood that the invention is not limited in the scope of its application to the use of all of the steps nor to the particular order in which they have been described.

Having described my invention, what I claim as new and desire to secure by Letters Patent of the United States is:

1. The method of making a shoe which comprises assembling a lining together with an insole upon a last, fastening the upper edge of the lining to the last, lasting the lining, assembling a molded counter on the heel portion of the lining, subjecting the counter to yielding pressure to conform it accurately to the last and fastening it in place, assembling a limp box toe upon the toe portion of the lining and conforming it to the

shape of the last, trimming off the surplus marginal material of the box toe, assembling an upper over the lining, box toe and counter, lasting the upper, pulling the last, fastening the lining and the upper together along the edge of the foot-opening of the shoe, and trimming off the projecting portion of the lining.

2. The method of making a shoe which comprises assembling a lining together with an insole upon a last, lasting the lining, assembling a molded counter on the heel portion of the lining, subjecting the counter to pressure exerted upon its wings and its inturned flange to conform it accurately to the last and fastening it in place, assembling an upper over the lasted lining and the counter, lasting the upper, pulling the last, and fastening the lining and upper together along the edge of the foot-opening of the shoe.

3. The method of making a shoe which comprises assembling a lining together with an insole upon a last, fastening the upper edge of the lining to the last, lasting the lining, assembling a molded counter on the heel portion of the lining, subjecting the counter to pressure to conform it accurately to the last and fastening it in place, assembling an upper over the lasted lining and the counter, lasting the upper, pulling the last, fastening the lining and the upper together along the edge of the foot-opening of the shoe, and trimming off the projecting portion of the lining.

4. The method of making a shoe which comprises assembling a lining together with an insole upon a last, fastening the upper edge of the lining to the last, lasting the lining, assembling a molded counter on the heel portion of the lining, subjecting the counter to the action of deformable pressing means to conform it accurately to the last and fastening it in place, assembling an upper over the lasted lining and the counter, lasting the upper, pulling the last, fastening the lining and the upper together along the edge of the foot-opening of the shoe, and trimming off the projecting portion of the lining.

5. The method of making a shoe which comprises providing on a last an insole, a lining lasted thereto and a molded counter, subjecting the counter to the action of deformable pressing means exerted upon its wings and its inturned flange to conform it accurately to the last and fastening it in place, assembling an upper over the lining and the counter, lasting the upper, pulling the last, and fastening the lining and upper together along the edge of the foot-opening of the shoe.

6. The method of making a shoe which comprises providing on a last an insole, a lining lasted thereto and fastened along its upper edge to the last, and a molded counter, subjecting the counter to pressure to conform it accurately to the last, fastening it in place, assembling an upper over the lasted lining, lasting the upper, pulling the last, fastening the lining and the upper together along the edge of the foot-opening of the shoe, and trimming off the projecting portion of the lining.

7. The method of making a shoe which comprises providing on a last an insole, a lining lasted thereto and fastened along its upper edge to the last, and a molded counter, subjecting the counter to the action of deformable pressing means to conform it accurately to the last, fastening it in place, assembling an upper over the lasted lining, lasting the upper, pulling the last, fastening the lining and the upper together along the edge of the foot-opening of the shoe, and trimming off the projecting portion of the lining.

8. The method of making a shoe which comprises assembling a lining together with an insole upon a last, fastening the upper margin of the lining to the last, lasting the lining, assembling an upper upon the lasted lining, lasting the upper, removing the fastening means, pulling the last, fastening the lining and the upper together along the edge of the foot-opening of the shoe, and trimming off the projecting portion of the lining.

9. The method of making a shoe which com-

prises assembling an insole together with a lining upon a last, lasting the lining, placing on the toe portion of the lining a soft box toe which is capable of becoming hard and resilient, conforming the box toe to the toe portion of the last, trimming off surplus material from the lower margin of the box toe, assembling an upper on the lining and box toe, lasting the upper, pulling the last and fastening the lining and upper together along the edge of the foot-opening of the shoe.
